[57] CLAIM

The ornamental design for a cooler, as shown and described.

DESCRIPTION

FIG. 1 is a left side elevational view of a cooler showing my new design;

FIG. 2 is a left side elevational view thereof with the handle in an up position;

FIG. 3 is a perspective view thereof with the handle removed for clarity of illustration;

FIG. 4 is a front elevational view thereof; and,

FIG. 5 is a rear elevational view thereof.
The undisclosed right side view is a mirror image to the left side.

The undisclosed bottom view is unornamented.
